UNITED STATES PATENT OFFICE.

INGEBERT J. THOMSEN, OF MINDEN, NEBRASKA.

PNEUMATIC HORSE-COLLAR.

No. 816,761.

Specification of Letters Patent.

Patented April 3, 1906.

Application filed August 22, 1905. Serial No. 275,267.

To all whom it may concern:

Be it known that I, INGEBERT J. THOMSEN, a citizen of the United States, residing at Minden, in the county of Kearney and State of Nebraska, have invented certain new and useful Improvements in Pneumatic Horse-Collars, of which the following is a specification.

This invention relates to pneumatic horse-collars.

Two forms of pneumatic horse-collars have been introduced on the market, one having two separate air-pads and the other formed of but one pad. The first form has never been used to any extent, because it has been found almost impossible to inflate the pads so that the pressure will be square on each shoulder, that an escape of air from one pad places the strain on one shoulder, and for the further reason that much time and labor are consumed by having to inflate the pads separately. The second form is objectionable for the reason that when any extra pressure is put on one pad the air rushes to the opposite pad and upon the pressure being lessened rushes back again, thus suddenly shifting the strain from one side to the other, which is very tiresome to the horse.

The object of this invention is to provide a pneumatic horse-collar which is adapted to equalize the strain on the neck and shoulders of the animal by the gradual transfer of air from one pad to the other.

With this and other objects in view the present invention consists in the combination and arrangement of parts, as will be hereinafter more fully described, shown in the accompanying drawings, and particularly pointed out in the appended claims, it being understood that changes in the form, proportion, size, and minor details may be made within the scope of the claims without departing from the spirit or sacrificing any of the advantages of the invention.

In the drawings, Figure 1 is a view of my improved horse-collar. Fig. 2 is a view of the pneumatic pads. Fig. 3 is a cross-section on line 3-3 of Fig. 1 looking in the direction of the arrows. Fig. 4 is a cross-section of the restriction-passage between the two pads.

Referring to the drawings, in which like numerals of reference designate correspond-

ing parts, 1 is the stiffening - rim, which is formed of a leather casing 2, stuffed with straw 3. Formed integral with casing 2 is a second casing 4, adapted to receive and protect the inflatable pads 5, which are of the form and size of the usual straw-stuffed pads. These inflatable pads 5 are connected to each other at their bottom ends by a small metal tube 6, which is held in place by a larger tube 7, which securely holds the ends of pads 5 against the outer periphery of tube 6. To make the joint more secure, annular ribs 8 are provided on the ends of tube 6, which embed themselves into the material of the pads and form air-tight joints. In the forward wall of one of the pads is provided a valve 9, adapted to receive the connection of the pump by which the pads are inflated. This valve 9 is accessible from the outside through an aperture 10 in casing 4.

11 indicates the ordinary form of strip fastening for the collar.

It will be observed that when in use the pressure will under normal conditions be equal in both pads. Any extra pressure on one pad will cause the air to slowly escape through the restricted aperture in tube 6 to the opposite pad, thereby equalizing the pressure without the sudden shifting of strain, which is so fatiguing to the animal.

A needle-valve 12 regulates the flow of air from one pad to the other through the restricted air-passage 6.

Having thus described my invention, what I claim, and desire to secure by Letters Patent, is—

1. The combination with a horse-collar of pneumatic pads connected by a restricted air-passage, and a valve controlling the passage of air through said air-passage.

2. In a pneumatic horse-collar, the combination with a rim portion of pneumatic pads connected by a restricted air-passage, and a valve controlling the passage of air through said air-passage.

3. In a pneumatic horse-collar, the combination with a stiff rim portion, of pneumatic pads secured to the under side thereof, a restricted air-passage connecting said pads, a valved aperture in one of said pads through which the air is introduced, and a needle-valve controlling the passage of air through said restricted air-passage.

4. In a pneumatic horse-collar, the combination with a stiff portion, of pneumatic pads secured to the under side thereof, a pipe forming a restricted air-passage connecting

5 said pads, a metallic casing surrounding said pipe, a needle-valve mounted in said casing and controlling the flow of air through said restricted air-passage and a valved aperture

in one of said pads through which air is introduced. 10

In testimony whereof I affix my signature in presence of two witnesses.

INGEBERT J. THOMSEN.
